UNITED STATES PATENT OFFICE

ARTHUR P. PAINE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

INTERMITTENT NEEDLE MOTION FOR AXMINSTER LOOMS

Application filed July 5, 1928. Serial No. 290,331.

This invention relates to improvements in needle motions for Axminster looms and it is the general object of the invention to provide a mechanism cooperating with the usual driving crank arm and having two successive substantially similar motions for each complete reciprocation of the needle, each motion starting and stopping gradually. The retardation due to the mechanism is added to that of the crank arm, one motion ending as the needle comes to rest in the shed and the other motion starting while the needle is still in the shed. In this way two retardations of the mechanism are added to the slight dwell or pause characteristic of the crank arm to increase the time during which the needle is in position to cooperate with the selvage shuttle. This increased dwell permits the loom to be run at a faster rate of speed.

Heretofore the dwell of the needle when the latter is in the shed has been accomplished by the retarding due only to the crank motion when the latter passes through one of its extreme positions. It is an important object of my present invention to retain this retarding due to the crank, but to add to it a retarding due to a form of Geneva motion employing two spaced pins which operate to give the star wheel two consecutive movements for a complete inserting and withdrawing motion on the part of the needle.

The ordinary Axminster loom operates to lay three double picks of filling for each tuft forming cycle and these picks are usually laid at irregular intervals. When wide looms of the type referred to were first built they operated approximately at eighteen tuft forming operations per minute and at this comparatively low rate of speed it was possible to have the picks laid at regular intervals. Later, when the speed of the loom was increased to twenty-seven tuft forming operations per minute it was found that insufficient time was afforded between the successive needle motions to permit a proper dipping of the tube frame, this dipping involving disconnecting the tube frame from the chain and moving it toward the cloth and inserting the yarn tubes through the warp threads. In order to afford more time for this operation,

therefore, the pick of filling which followed the dipping was delayed. The pick following the second step in the tuft forming operation, which involves combing up, pinching the tuft yarns by the reed and drawing off, did not need to be delayed as much as the first pick. The third pick in the tuft forming cycle takes place when no operations affecting tuft formation are taking place in the loom, and for this reason the third pick may be laid as quickly as will be permitted by the weight of the needle and its operating parts.

It is a further object of my invention to provide a Geneva motion of modified form having a pin wheel with actuating pins located at different arcuate distances around the pin wheel so that the star wheel which is operatively connected to the needle will be given operating movements at unequal intervals.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a front elevation of the needle motion, parts being removed for the sake of clearness,

Fig. 2 is an enlarged vertical section on line 2-2 of Fig. 1 looking in the direction of the arrows and showing the parts in the position they assume just prior to the weft laying movement of the needle of the pick immediately following the dipping of the tube frame toward the fabric to start movement of the needle into the shed,

Fig. 3 is a view similar to Fig. 2 but with the star wheel moving around to the left 90°, this position corresponding to the needle when the latter is entirely in the shed and is just starting on its return, as shown in Fig. 1,

Fig. 4 is a horizontal section on line 4-4 of Fig. 3.

Referring particularly to Fig. 1, I have shown the needle motion frame 10 which is ordinarily located on the right hand side of

a wide Axminster loom. The frame 10 supports a needle rail 11 along which moves a needle carriage 12 actuated back and forth by means of a cable 13. The left hand end 5 of the cable is trained around a guide sheave 14 rotating about a fixed stud 15 and is attached to an oscillating drum 16.

The right hand end of the cable is trained around a movable guide sheave 17 which rotates about a stud 18 carried by depending arm 19 of a take-up lever 20. The latter swings about fixed stud 21 carried by an up-standing horn 22 supported by the needle rail 11. The take-up lever is provided with a ratchet 23 which cooperates with a hold pawl 24 pivoted at 25 to the needle rail, and a weight 26 acts constantly on the lever 20 tending to move the sheave 17 to the right as viewed in Fig. 1. That end of the cable 20 which extends from the under side of the movable sheave is also secured to the drum 16 so that as the latter rotates first in one direction and then in the other the needle carriage 12 reciprocates along the needle rail.

25 The drum is secured to a shaft 27 supported by the frame 10 and having secured to the forward end thereof a driving pinion 28. The latter meshes with a segment gear 29 which rocks about a stud 30 secured to the frame 10. By means of a connector 31 adjustably connected to the segment as at 32 and pivoted to revolving crank arm 33 the segment is moved first to the right and then to the left to cause the previously described 35 reciprocations of the needle carriage 12. The crank arm 33 is keyed to a shaft 34 which is journaled on the frame 10.

On the opposite side of the loom from that on which the needle motion is located there is 40 provided the selavage shuttle which interloops with the filling to hold the latter. The shuttle is actuated by an upright oscillating shaft 35 caused to rock first in one direction and then in the other by mechanism not shown. 45 A head 36 is keyed to the shaft 35 to cause the shuttle S to move under the needle N. The weft W which passes through the eye 37 of the needle is looped as suggested at the left hand end of Fig. 1 so that the shuttle may 50 pass therethrough.

The shaft 35 is so manipulated as to cause the shuttle to have a traversing motion with the needle as in the position shown in Fig. 1 or entirely through the shed. It will be understood that it is desirable to have a slight pause in the motion of the needle when in the shed to permit the shuttle S to move through the loop of weft.

The matter thus far described is common 60 construction in the needle motion of wide Axminster looms and forms no part of my present invention, the parts being so timed and operated that the carriage 12 will be moved into and out of the shed at the proper times and the shuttle S being actuated

to hold the filling as the needle is withdrawn from the shed.

As previously stated, my present invention relates to means for effecting the proper dwells or retardations in the motion of the needle and more particularly to the means for imparting motion to the crank arm 33 of such character as to effect the proper motion of the needle. In carrying my invention into effect I secure to the continuously and preferably uniformly rotating driving shaft 38, which is an ordinary part of the loom, a plate 50, see Fig. 4, which is secured to the shaft by a key 51 and held against longitudinal movement with respect thereto by screw 52. Said plate 50 has secured thereto three pairs of rolls or pin members which in effect take the place of the pin in an ordinary Geneva motion. The pairs of rolls or pin members are designated herein at A, B and C and each roll 53 is held to the plate by means of a stud 54 having a head 55 which limits upward movement of the roll. That part of the stud 54 which extends through the plate is reduced as at 56 to present a shoulder 57 to engage the plate. A nut 58 holds the stud 54 in position and the roll 53 is so proportioned as to be freely rotatable on this stud. Each of the rolls of the three pairs is preferably made in the same way and as set forth particularly in Fig. 4.

In Figs. 2 and 3 it will be seen that a short space D is located between the pairs A and B, an intermediate space E is located between the pair B and C, and the long space F is located between the pair of rolls C and A. The purpose of this will be set forth hereinafter but it is to be understood that although the pairs are unevenly distributed angularly around the driving shaft 38 yet the rolls or pin members of any one pair are the same distance apart as are the rolls of any other pair.

The rolls or pin members are adapted for cooperation with a star wheel indicated generally at 60, said star wheel as shown herein having four grooves 61, 62, 63 and 64, respectively. The star wheel is preferably cast integral with a bevel gear 65 and is freely rotatable on a fixed stud 66 which is supported by bearings 67 and 68, respectively, and is held against rotation and in proper longitudinal position by a set screw 69 extending through the bearing 68.

The star wheel 60 is provided between the grooves thereof with a plurality of rocking arcuate faces 70 each of which when nearest the driving shaft 38 will be concentric with the axis of the latter. Cooperating with the locking arcuate faces 70 is a disk 71 secured to the plate 50 by means of bolts 72 and having locking surfaces 73, 74 and 75 which are, respectively, relatively short, intermediate and long. The disk is recessed between the arcuate locking faces as at 71' to provide clear-

ance for the star wheel when the latter is rotated, said recesses being of substantially the same length and being adjacent the pairs of rolls.

5 The shaft 34 to which the crank arm 33 is secured has mounted thereon a bevel pinion 80 which meshes with the bevel gear 65 and said pinion is secured to the shaft 34 by means of a key 81 so that as the star wheel rotates 10 the arm 33 is caused to rotate about the shaft 34. As shown in Fig. 4 the rear end of the shaft 34 may be supported by the bearing member 67.

In operation, as previously stated, it may be 15 desirable to produce dwells of differing lengths in the motion of the needle when the latter is out of the shed, and it is furthermore necessary to produce a slight dwell which is preferably of the same duration for 20 each pick of the loom when the needle is inserted in the shed and is in position to cooperate with the selvage shuttle. During the time that the tube frame not shown is being moved toward the fabric the needle must be 25 kept at rest for its greatest length of dwell, and during this time the space F as shown in Fig. 3 will be moving in a right hand direction around the shaft 38 past the star wheel 60 with the surface 75 locking the star wheel.

30 As soon as the needle has been dipped it is necessary to lay a pick of filling and the advancing or leading roll 53 of the pair C will enter the slot 63 as suggested in Fig. 2. This entry of the roll in the slot takes place 35 when the trailing or following end of the face 75 is substantially in line with the centers of the shafts 38 and 66 so that the star wheel will be free to rotate without interference on the part of the locking disk 71. By 40 the character of the motion peculiar to a pin and star wheel the star wheel will start with a rather gradual motion which will increase until the driving pin reaches the line joining the centers of shafts 38 and 66, after 45 which further movement of the pin will result in a retarding of the star wheel and therefore the needle. As the disk or pin wheel 50 continues to rotate the parts will assume the positions shown in Fig. 3 with the leading 50 roll 53 of the pair C leaving slot 63 and the trailing roll of the same pair just entering slot 64. By this motion the needle is moved into the shed.

55 As the disk 50 continues to rotate from the position shown in Fig. 3 to the right the trailing roll 53 will bring about a motion on the part of the star wheel similar to that caused by the advancing roll and when the trailing roll reaches the position where it is to move out of the slot 64 the locking surface 74 will engage the locking surface of the star wheel located between the disks 61 and 64. The motion just described moves the needle out of the shed.

60 There is produced by this arrangement an

appreciable dwell in the motion of the needle when the latter is in position to cooperate with the selvage shuttle. It will be noted that the dwell due to the inherent properties of the pin and star wheel motion as already described comes at the same time that the crank arm 33 and connector 31 are in substantial alignment, so that the dwell on the part of the needle is due in part to the nature of the motion derived from the pin and star wheel motion, and in part due to the natural retardation incident to the rotation of the crank arm 33.

65 As the shaft 38 and therefore the disk continues its rotation the pairs of rolls or pin members B and A will successively actuate the star wheel, the dwell in the motion of the star wheel when the needle is out of the shed being dependent upon the spaces between the pairs.

70 It is to be understood that two successive angular movements of the star wheel caused by the two rolls or any pair are necessary in order to effect a complete reciprocation of the needle end. The crank arm 33 and star wheel 60 will be so placed with respect to each other that when the crank arm extends to the right of the shaft 34 as viewed in Fig. 1, or in the opposite direction from that shown in Fig. 1, the star wheel will be in position to be engaged by the advancing roll of a pair of rolls. As the advancing roll or pin member moves to effect a one-quarter rotation of the star wheel the crank arm will move in a right hand direction to the position shown in Fig. 1, which corresponds to the inserting movement of the needle. As the trailing roll brings about the second angular movement of the star wheel the crank arm 33 will be moved from the position shown in Fig. 1 to the right through 180° to withdraw the needle. Because of the relation of the star wheel and crank it is desirable that the bevel gear 65 have twice as many teeth as the pinion 80 which meshes therewith so that a movement of 90° on the part of the star wheel and bevel pinion 65 will produce a movement of 180° on the part of the shaft 34, crank arm 33 and bevel pinion 80.

75 Although the rolls 53 are shown herein yet I may if desired employ pins fixed relatively to the plate 50, this result being accomplished merely by engaging the stud 54 and for this reason I prefer to refer to the disk 50 as a pin wheel to mesh with the star wheel 60.

80 From the foregoing it will be seen that I have provided a modified pin and star wheel motion wherein for each pick of the weft laying needle two actuating pins or rolls will cooperate with the star wheel to give the latter two successive angular movements for each complete reciprocation of the needle, the effect being to produce on the part of the needle when the latter is cooperating with the selvage shuttle a slight dwell due to the nature of the

motion derived from the pin and star wheel movement. It will further be seen that the retardation due to the pin and star wheel motion is added to that of the crank arm 33, so that both of these mechanical devices contribute to the retarding of the needle when the latter is in the shed. Again, it will be seen that the locking surfaces 73, 74 and 75 which are fast with respect to the pin wheel are of different lengths so as to hold the star wheel locked for varying angular intervals during the movement of the driving shaft 38. While I have shown the star wheel as having four slots and the bevel gear and pinion as having a ratio of two to one as a result of the particular number of slots shown in the star wheel, yet I do not wish to be limited to this relation, as it will be sufficient for the purposes of my present invention if the fractional rotation caused by the successive operation of the pair of rolls represents the ratio of the gear 65 relatively to the pinion 80. It will further be seen that by unevenly distributing the pairs of rolls or pinions around the pin wheel I secure the dwells of varying lengths on the part of the needle when the latter is out of the shed to accommodate the successive tuft forming operations which follow in sequence in any tuft forming cycle of the loom. The uneven distribution of the pairs of pin members, however, is not an essential part of my present invention.

Having thus described my invention it will be seen that changes and modifications may be made therein by those skilled in the art without departing from the spirit and scope of the invention and I do not wish to be limited to the details herein disclosed, but what I claim is:

- 40 1. In a needle motion for a loom, a continuously rotating pin wheel, a pair of spaced pin members secured to and moving with the pin wheel, a star wheel to cooperate with the pin members, a needle operatively connected to the star wheel, one of said pin members to act on the star wheel to move the needle in one direction, and the other pin member to act on the star wheel to move the needle in the opposite direction.
- 45 2. In a needle motion for looms, a continuously moving pin wheel, a pair of spaced pin members secured to and moving with the pin wheel, a star wheel, a needle operatively connected to the star wheel, said pin members cooperating with the star wheel to give the same two successive angular movements to effect a complete reciprocation of the needle into and out of the shed of the loom.
- 50 3. In a needle motion for looms a continuously moving pin wheel, a pair of pin members secured to the pin wheel in spaced relation and located at substantially equal distances from the axis of the wheel, a star wheel, a needle operatively connected to the star wheel, the leading pin member of the

pair producing a given angular movement on the part of the star wheel as the pin wheel rotates to move the needle into the shed, and the other pin member acting on the star wheel to give the same a second angular movement effective to move the needle out of the shed.

4. In a needle motion for looms, a continuously moving pin wheel, a pair of spaced pin members secured to and moving with the wheel, a star wheel to be given two successive motions of equal angular displacements by the pin members as the pin wheel rotates, a needle, and mechanism connecting the needle and star wheel and effective to cause movement of the needle in one direction during the first movement of the star wheel and effective to cause reverse movement of the needle during the second movement of the star wheel.

5. In a needle motion for looms, a continuously moving pin wheel, a pair of spaced pin members secured to and moving with the wheel, a needle, a revolving crank arm operatively connected to the needle, a star wheel operatively connected to the crank arm, said pin members acting on the star wheel to give the latter two successive movements of substantially equal angular displacements, the first movement of the star wheel being effective to move the crank through a half revolution to effect movement of the needle in one direction and the second movement of the star wheel being effective to move the crank through another half turn to effect reverse movement of the needle.

6. In a needle motion for looms, a continuously moving pin wheel, a pair of spaced pin members secured to and moving with the wheel, a needle to be reciprocated, an oscillating segment operatively connected to the needle, a rotating crank arm operatively connected to the segment and effective during a complete revolution thereof to produce a complete reciprocation of the segment and needle, a star wheel to cooperate with the pin members and receive two successive movements of substantially equal angular displacements from the pin members, the first pin member when giving the star wheel the first angular movement being effective to move the crank through a half revolution to effect a complete movement of the oscillating member and needle in one direction, and the second pin member when giving the star wheel the second angular movement effective to give the oscillating member and needle a reverse motion.

7. In a needle motion for looms, a continuously moving pin wheel, a pair of spaced pin members secured to and moving with the wheel, a needle to be reciprocated, a star wheel to cooperate with the pin members and to be given two successive movements of equal angular displacement by said pin members as the pin wheel rotates, meshing geared ele-

ments interposed between the star wheel and the needle effective to move the needle in one direction during the first movement of the star wheel and to move the needle in the opposite direction during the second movement of the star wheel.

8. In a needle motion for looms, a continuously moving pin wheel, a pair of spaced pin members secured to and moving with the wheel, a needle to be reciprocated, a star wheel having a plurality of pairs of elements to cooperate with the pin members, said pin members as the pin wheel rotates being effective to engage a pair of elements on the star wheel to give the latter two successive movements of substantially equal angular displacements, and mechanism interposed between the star wheel and the needle to move the latter in one direction during the first motion of the star wheel and to move the needle in the opposite direction during the second movement of the star wheel.

9. In a needle motion for looms, a continuously moving pin wheel, a pair of spaced pin members secured to and moving with the wheel, a needle to be reciprocated, a star wheel having a plurality of pairs of elements to cooperate with the pin members, said pin members as the pin wheel rotates being effective to engage a pair of elements on the star wheel to give the latter two successive movements of substantially equal angular displacements, and mechanism interposed between the star wheel and the needle to move the latter in one direction during the first motion of the star wheel and to move the needle in the opposite direction during the second movement of the star wheel, said mechanism including two geared elements having unequal numbers of teeth, the ratio between the teeth of the geared elements being dependent upon the number of pairs of elements on the star wheel.

10. In a needle motion for looms, a continuously moving pin wheel, a pair of spaced pin members secured to and moving with the wheel, a needle to be reciprocated, a star wheel having a plurality of pairs of elements to cooperate with the pin members, said pin members as the pin wheel rotates being effective to engage a pair of elements on the star wheel to give the latter two successive movements of substantially equal angular displacements, and mechanism interposed between the star wheel and the needle to move the latter in one direction during the first motion of the star wheel and to move the needle in the opposite direction during the second movement of the star wheel, said mechanism including two gears of unequal diameter one of which is fast relatively to the star wheel, the diameter of the larger gear fast with the star wheel with respect to the other being a multiple of the diameter of the smaller gear, the multiple being the same as the number of pairs of elements on the star wheel.

11. In a needle motion for looms, a continuously moving pin wheel, a plurality of pairs of pin members on the pin wheel, the members of each pair being equally spaced, a needle, a star wheel to be given two successive movements by each pair of pin members and mechanism interposed between the star wheel and the needle and operatively connecting these parts and effective during the first movement of the star wheel to move the needle in one direction and effective during the second movement of the star wheel to move the needle in the opposite direction.

12. In a needle motion for looms, a continuously moving pin wheel, a plurality of pairs of pin members on the pin wheel, the members of each pair being equally spaced, a needle, a star wheel to be given two successive movements by each pair of pin members and mechanism interposed between the star wheel and the needle and operatively connecting these parts and effective during the first movement of the star wheel to move the needle in one direction and effective during the second movement of the star wheel to move the needle in the opposite direction, the pairs of pin members being unequally spaced angularly around the axis of the pin wheel.

In testimony whereof I have hereunto affixed my signature.

ARTHUR P. PAYNE.
